UNITED STATES PATENT OFFICE

2,638,074

MECHANICAL PENCIL WITH SPIRAL FEEDING MEANS

Hugo S. Hasselquist, Oak Park, Ill., assignor to
Joseph Dixon Crucible Company, Jersey City,
N. J., a corporation of New Jersey

Application September 3, 1948, Serial No. 47,610

1 Claim. (Cl. 120—18)

1

This invention relates to mechanical pencils with spiral feeding means.

One object of the invention is to provide a pencil of the character described having novel and efficient means for supporting and frictionally engaging and gripping the lead in the tip in a manner to prevent it from falling out.

Another object of the invention is to provide a pencil of the character described having the barrel, spiral, tip and lead guide and support so assembled and mounted that they will be maintained in correct alignment and will be effectively held in the proper assembled relation with reference to each other.

Further objects of the invention will appear from the following specification taken in connection with the drawings which form a part of this application, and in which:

Fig. 1 is a longitudinal sectional elevation of a mechanical pencil constructed in accordance with the invention, the lead feeding member being shown in this view in its extreme position of retraction;

Fig. 2 is a longitudinal sectional elevation similar to Fig. 1 but showing the lead feeding member in operative position feeding the lead;

Fig. 3 is an enlarged elevational view of the lead guiding and gripping member inserted in the pencil tip;

Figs. 4, 5 and 6 are respectively transverse sectional elevations, on an enlarged scale, taken substantially on lines 4—4, 5—5 and 6—6 of Fig. 2, looking in the direction of the arrows;

Figs. 7 and 8 are respectively a longitudinal section and an end elevation of the lead supporting and gripping member shown in Fig. 3; and

Fig. 9 is a longitudinal sectional elevation of a modified form of spiral.

In the embodiment of the invention illustrated in the drawings, the pencil comprises a barrel 10, which may be formed of any suitable material, such as wood, plastic or metal. The front end of the barrel 10 is tapered, as shown at 11, and receives a tapered or conical end 12 of the pencil tip 13. The tip 13 at its outer end has a cylindrical bore 14 which receives a tubular lead guiding member 16. The lead guiding member 16 has at its outer end a cylindrical bore 17 for guiding the lead and is provided with a pair of inwardly bent resilient fingers 18 and 19 which grip the lead and prevent the lead from falling out. The outer end of the tip 13 is beveled, as shown at 20, and the outer end of the member 16 is also beveled, as shown at 21, these two bevels being formed on the same angle and merging, as clearly shown in the drawings.

2

The barrel 10 houses a cylindrical spiral 25 having a spiral slot 26 extending throughout the length thereof. The front end of the spiral 25 is anchored in a collar 27 which fits into the tapered portion 12 of the tip 13 and is held therein by lugs or prongs 28. The collar 27 has a notch 29 at its front edge which receives the outwardly bent end 30 of the spiral 25. The engagement of the end 30 with the notch 29 prevents the spiral 25 from rotating relative to the collar 27.

The rear end of the spiral 25 is anchored by a collar 35 which abuts against the rear end of the barrel 10. The spiral 25 extends through the collar 35 and the outer end of the spiral strip is bent laterally, as shown at 36, to anchor the spiral in the collar. From the foregoing description it will be clear that the spiral 25 is anchored in the barrel 10 by the collars 27 and 35.

A modified form of spiral strip is shown in Fig. 9. In this form the edges of the strip 50 forming the spiral have inwardly extending flanges or beads 51 which stiffen or strengthen the strip and also form supports for the lead.

The rear end portion of the barrel is reduced in section, as shown at 37, and receives a cap 38 having an opening 39 in its outer end aligned with the spiral 25 so that in order to refill the pencil it is merely necessary to drop the lead through the opening 39 into the spiral 25. This is done after the lead feeding member 40 has been retracted to the position shown in Fig. 1.

The lead feeding member 40 consists of a longitudinally extending body portion 41 having lugs or projections 42 and 43 at the front and rear ends thereof. These lugs extend into a longitudinal groove 44 formed in the inner wall of the barrel 10. At its front end the body portion 41 has an inwardly extending lug 45 adapted to be positioned in one portion of the spiral slot in the spiral 25 and at its rear end adjacent the lug 43 the body portion 41 has an inwardly extending finger 46 which extends through the slot 26 and into the spiral when the lead feeding member is in operative position, as shown in Fig. 2. When the feeding member is retracted, the lug 43, in conjunction with the conical surface 47 of the collar 35, causes the rear end of the feeding member to be swung outwardly, thereby withdrawing the lead feeding finger 46 from the spiral to permit lead replacements to be fed into the rear end of the spiral through the cap opening 39.

In order to feed the lead in the pencil, the barrel 10 is rotated relative to the tip 13 or vice versa. This relative rotation causes the lead feeding member 41 to be fed along the spiral 25 since the spiral is fixed relative to the tip and as the tip

is rotated the lugs 42 and 43 will move along the groove 44 in the barrel and the rotation of the spiral will cause the lead feeding member to move along the spiral.

The collar supports the outer end of the spiral 25 and is rotatably supported in the cap 38. The cap thus forms a bearing for the collar.

Although one specific embodiment of the invention has been particularly shown and described it will be understood that the invention 10 is capable of modification and that changes in the construction and in the arrangement of the various cooperating parts may be made without departing from the spirit or scope of the invention, as expressed in the following claim.

What I claim is:

In a mechanical pencil, a barrel, a lead supporting and guiding spiral therein, a tip on the front end of the barrel, means in the tip for supporting the front end of the spiral, said spiral 20 projecting beyond the rear end of the barrel, lead feeding means in the barrel having a portion engageable with the spiral to feed the lead, said feeding means having a spiral engaging portion, a lead engaging portion, and an outwardly and 25 rearwardly extending lug, and a collar on the projecting rear end of the spiral disposed in abutting relation to the rear end of the barrel, said collar having a tapered surface engageable with the lug of the lead feeding means when said means is 30

retracted to lift the lead engaging portion thereof out of the spiral, said barrel having a surface on its rear end engaging the lug to move the lead engaging portion of the lead feeding means to operative position.

HUGO S. HASSELQUIST.
